G. P. ALTBURG,
HEAT INSULATED VESSEL AND CASING THEREFOR.
APPLICATION FILED JAN. 31, 1919.

1,353,305.

Patented Sept. 21, 1920.

Inventor:

George P. Heuberg,
By D. Heuberg.

Attorney.

UNITED STATES PATENT OFFICE.

GEORGE P. ALtenBERG, OF CINCINNATI, OHIO, ASSIGNOR TO THE ICY-HOT BOTTLE COMPANY, OF CINCINNATI, OHIO, A CORPORATION OF WEST VIRGINIA.

HEAT-INSULATED VESSEL AND CASING THEREFOR.

1,353,305.

Specification of Letters Patent. Patented Sept. 21, 1920.

Application filed January 31, 1919. Serial No. 274,305.

To all whom it may concern:

Be it known that I, GEORGE P. ALtenBERG, a citizen of the United States, residing at Cincinnati, in the county of Hamilton and State of Ohio, have invented certain new and useful Improvements in Heat-Insulated Vessels and Casings Therefor, of which the following is a specification.

My invention is particularly applicable to vacuum-insulated pots or pitchers, or similar vessels, hereinafter for convenience referred to as pots, adapted for serving coffee, chocolate, tea, milk, cream, or other beverages.

It is the object of my invention to provide new and improved means for connecting the mouth-end of the inner vessel of a heat-insulated pot with its outer casing in such manner that the inner vessel may be removed, and that a leakless joint may be provided between the inner vessel and the pouring wall of the casing.

It has been difficult in vessels of this character to provide connecting means between the mouth of the inner vessel and the pouring wall of the casing which properly relatively locate the parts and prevent the contents of the inner vessel seeping or leaking through the joint between the inner vessel and the pouring wall of the casing. I avoid these objections by means of my invention, and at the same time provide a joint in which the various parts are readily assembled and replaced, and are readily accessible for cleaning purposes, and furthermore provide a tight joint regardless of inequalities there may be in the mouth-end of the inner vessel, it being understood that in practice it is difficult, in fact, impossible to infallibly provide the inner wall and outer wall of the inner vessel with a cross-seal at the mouth which is accurate or regular throughout its circumference, the end-surface of the mouth usually being either uneven, for instance, one portion thereof being higher than another, the diameters of the mouth-ends also varying in practice. All these irregularities and unevennesses are compensated for in my invention, and may be disregarded in assembling the parts.

The present invention is an improvement upon the inventions shown, described and claimed in my applications for patents on improvements in casings for vacuum-insulated vessels, Serial No. 154,027, and in vac-

uum-insulated vessels and casings therefor, Serial No. 154,028, both filed March 10, 1917.

The present invention is directed more particularly to a resilient cushion-ring positioned between the mouth of the inner vessel and the pouring wall of the casing, the latter having a radially inwardly extending flange provided with a drain surface, said flange having an axially inwardly projecting annular inner edge or bead projecting toward the end surface of the mouth of the inner vessel. The cushion-ring is provided with a radially inwardly extending resilient lip. Means are provided for pinching the latter lip between the end surface of said mouth of the inner vessel and the inwardly or downwardly extending inner edge or bead of the drain wall of the casing.

The invention will be further readily understood from the following description and claims, and from the drawings, in which latter:

Figure 1 is a side elevation of a pot embodying my invention, partly broken away, and partly shown in central vertical section on the line 1—1 of Fig. 2.

Fig. 2 is a plan view of the same, partly broken away and partly in section on the line 2—2 of Fig. 1; and,

Fig. 3 is an enlarged view of the joint between the mouth ends of the inner vessel and the casing, shown in vertical section on the line 1—1 of Fig. 2.

In the present exemplification of my invention, the body comprises a casing 11, and an inner vessel 12, the inner vessel being shown as a heat-insulated vessel comprising an inner wall 13 and an outer wall 14, having a vacuum-insulated space 15 therebetween, the inner and outer walls being connected at the mouth of the vessel by an annular cross-seal 16. The vessel is usually of frangible material, such as glass. The cross-seal is, in practice, liable to have variations therein in a plane perpendicular to the axis of the vessel, owing to the usual methods of manufacture of vessels of this character. The inner surface of the wall of the space may be provided with a usual silver coating.

In the present exemplification, the casing comprises an upper member 20 and a lower member 21 within which the inner vessel is received. The casing-members are de-

tachably connected by suitable means, which have the function of drawing the casing-members one toward the other in the direction of the axis of the casing, these connecting means being exemplified as a threaded connection 22, the interengaging threads being on the respective members, the annular end 23 of one of the members being arranged to contact an annular shoulder 24 on the other member.

10 The casing is provided with a pouring wall 27, shown as a downwardly extending inwardly sloping closed wall, provided with a pouring channel 28, the said wall terminating at its lower end in an inner laterally and preferably slightly downwardly extending flange 29. The inner edge of this flange is provided with an axially or downwardly extending annular closed 20 edge or bead 30.

15 The casing preferably comprises a neck 31, the inner surface of which preferably tapers upwardly toward the axis of the pot, the upper end of this tapering neck 25 being spaced radially from the inner edge of the pouring flange, forming an annular space 32 between said edge and said neck of the casing.

20 A resilient cushion-ring 35, instanced as 30 a rubber ring, is received in this space under the pouring flange between the outer face of the neck 31 of the vessel and the inner face of the neck of the casing.

25 The cushion-ring is provided with a radially inwardly extending resilient lip 37 which is received over the mouth-end of the inner vessel, so as to locate the inner edge of said resilient lip between the cylindrical projections of the inner and outer 35 faces of the neck of the inner vessel, being, in the present instance, located on the cross-seal between the inner and outer walls of the inner vessel. The upper inner portion 40 of this cushion-ring is preferably rounded 45 below its lip, as shown at 38, for being snugly received over the annular rounding of the upper outer edge of the mouth of the inner vessel.

50 The position of the resilient lip, when the parts are assembled, is preferably substantially coincident with the inner downwardly axially projecting edge or bead of the pouring flange, being so arranged that the inner edge of the resilient lip is pinched 55 between said inner edge or bead of the casing and the upper face of the mouth of the inner vessel when the parts are assembled. This assembling is accomplished in such manner as to cause the mouth of the inner vessel and the inner edge of the pouring wall of the outer vessel to be drawn one toward the other, exemplified as accomplished by the screw-connection between the upper and lower sections of the casing. When assembled, the extreme inner edge of the pour-

ing flange preferably extends inwardly to slightly greater extent than the inner edge of the resilient lip for forming a slight annular groove 39 between said first-named inner edge and the mouth-end of the inner vessel, in order to remove said inner edge of said resilient lip from direct contact by the passing liquid. The resilient cushion-ring 35 and its resilient lip 37 are preferably integral with one another and compressible. The casing-parts are preferably of metal.

10 In order to provide for ready assembling of the parts and for variations in lengths between the inner vessel and the casing and 80 to resiliently hold the inner vessel in the casing, I provide cushion means between the lower end of the inner vessel and the bottom of the lower member of the casing, exemplified as comprising a volute spring 85 41, positioned in the depending bottom 42 of the lower member of the casing, the upper end of the spring being provided with a cushion-pad 43, for instance of cork, in which the lower end of the inner vessel 90 is seated.

15 The action of the tapered inner face of the neck of the casing is to position the cushion-ring centrally with relation to the mouth-end of the casing, and also to cause 95 inward lateral pressure on the cushion-ring radially toward the axis of the inner vessel to crowd the upper face of the cushion-ring inwardly, or prevent crowding of the same outwardly, in order to position the 100 radially inwardly extending resilient lip with relation to the inner edge or bead of the pouring wall of the mouth of the casing, and to prevent an undue retraction radially outward of said resilient lip when 105 pressure is exerted between the inner vessel and the inner edge or bead of the pouring flange in assembling the parts.

20 The pouring wall and its flange have a continuously downwardly and inwardly 110 sloping upper face discharging toward the downwardly and inwardly sloping face of the cross-seal for readily draining any liquid thereon into the vessel, the edge surface of the resilient lip presented to the liquid contents of the inner vessel being negligible, so that there is no danger of contaminating the contents or injuring the resiliently yielding connection or seal between the mouth of the inner 115 vessel and the pouring wall of the casing.

25 The casing parts are readily separated and the inner vessel and the resilient cushion ring are readily removed for cleaning purposes and for replacement or renewal of 125 parts.

30 The casing is preferably provided with a cover 45, exemplified as hinged to the casing by means of a hinge 46, as more fully shown, described and claimed in my afore- 130

said applications. The casing may be provided with a suitable handle 47.

Having thus fully described my invention, what I claim as new and desire to secure by Letters Patent, is:

- 5 1. In a heat-insulated vessel, the combination of an inner vessel and a casing therefor, said inner vessel comprising a mouth, said casing comprising a downwardly inwardly sloping closed pouring wall provided with an inwardly extending closed lip, a compressible cushion between said mouth of said inner vessel and said casing provided with a compressible lip received 10 between said first-named lip and said mouth of said inner vessel, and means whereby to pinch said compressible lip between said first-named lip and said mouth of said inner vessel, the inner edge of said first-named lip extending inwardly beyond the inner edge of said compressible lip, and said first-named lip spaced from said mouth of said inner vessel to form a slight inner groove between said first-named lip and said 15 mouth.
- 20 2. In a heat-insulated vessel, the combination of an inner vessel and a casing therefor, said inner vessel comprising a mouth having an upper end which is rounded in cross-section, said casing comprising a downwardly and inwardly sloping closed pouring wall provided with an inwardly extending closed lip provided with a bead at its inner closed edge, said bead projecting 25 toward said inner vessel and arranged to contact with said rounded upper end of said mouth, a resilient compressible cushion-ring between said mouth of said inner vessel and said casing provided with a resilient compressible lip received between said bead and said rounded upper end of said mouth of said inner vessel, and means whereby to pinch said resilient compressible lip between the inside of said vessel between said mouth and said first-named lip.
- 30 3. In a heat-insulated vessel, the combination of an inner vessel comprising a mouth, a casing therefor comprising a downwardly and inwardly sloping closed pouring wall provided with an inwardly extending closed 35 pouring lip, a cushion received about said mouth of said inner vessel having a radially inwardly extending closed cushion lip received between said first-named lip and said mouth of said inner vessel, said first-named lip provided with an axially inwardly extending bead at its inner edge arranged to coat with said lip of said cushion, the inner edge of said closed pouring lip being of greater diameter than the inner edge of said closed cushion lip, and means whereby 40 to pinch said lip of said cushion between said bead and said mouth of said inner vessel.
4. In a heat-insulated vessel, the combination of an inner frangible vessel comprising a neck terminating in a mouth, a casing therefor comprising a neck the inner wall of which tapers toward said mouth, a drip wall having a radially inwardly extending lip provided with an axially downwardly extending annular bead, a resilient compressible cushion-ring provided with a resilient compressible radially inwardly extending annular lip received between said axially downwardly extending annular bead 45 and said mouth of said inner vessel, and means to cause axial movement between said mouth and said axially downwardly extending annular bead whereby to press said resilient compressible lip between said mouth and said axially downwardly extending annular bead, and to cause radial inward confining pressure on said resilient compressible cushion-ring toward said mouth.
5. In a heat-insulated vessel, the combination of an inner vessel comprising an inner wall and an outer wall connected by a cross-seal at the mouth of said inner vessel and having a vacuum-insulated space between said walls, a casing for said vessel 50 provided with a lip releasably received over and around said mouth and having a radially outwardly and upwardly extending wall receding outwardly away from said mouth and forming a drain wall sloping 55 toward said mouth, said lip provided with a downwardly extending inner bead, a resilient compressible cushion-ring removably received about said mouth and provided with a resilient compressible radially inwardly extending lip received between said downwardly extending inner bead and said cross-seal, and means for pinching said resilient compressible lip between said bead and said cross-seal.

In testimony whereof I have hereunto signed my name in the presence of two subscribing witnesses.

GEORGE P. ALTENBERG.
